E. L. BARNES

ICE FORM

Original Filed Sept. 18, 1922

FIG. 1.

FIG. 2.

FIG. 3.

FIG. 4.

Eugene L. Barnes, INVENTOR

BY ATTORNEY

UNITED STATES PATENT OFFICE.

EUGENE L. BARNES, OF BUFFALO, NEW YORK.

ICE FORM.

Application filed September 18, 1922, Serial No. 588,780. Renewed December 26, 1925.

My invention relates in general to forms for manufacturing ice, and more particularly to forms for use in household refrigerating apparatus.

It is well known that in household refrigerating apparatus of the present day, provision is made for manufacturing small cubes of ice for table use. The drawers which are usually provided for this purpose have partitions which form a plurality of compartments in which the ice is made. When it is desired to use but a few pieces of ice, it is impossible to remove these without removing many more than are desired, since it is necessary to invert the drawers and knock the ice cubes from the receptacles. This not only results in a waste of ice but is very inconvenient, since the cubes must be placed back into the receptacles or the receptacles refilled with water and frozen.

The principal object of my invention has been to provide a device in which one or more cubes of ice may be removed without disturbing the others.

Another object has been to provide a device, in which practically all of the surfaces of the ice receptacles shall be exposed to the freezing temperature in the apparatus, whereby the time of freezing is greatly decreased.

Furthermore, my invention is inexpensive to manufacture; simple and convenient to use; and efficient in operation.

Moreover, my invention is of such a nature that all the parts thereof may be easily and thoroughly cleaned.

The above objects and advantages have been accomplished by the device shown in the accompanying drawings of which:

Fig. 1, is a side sectional elevation of the freezing chamber of a refrigerating apparatus, showing my device in place.

Fig. 2, is an enlarged plan view of my device with some of the ice receptacles removed.

Fig. 3, is a side elevation of the device partly broken away.

Fig. 4, is a transverse, sectional elevation taken on line 4-4 of Fig. 3.

In the drawings, 5 represents the freezing chamber of a refrigerating apparatus in which is provided a compartment 6, having a bottom 7 and a top 8. An opening 9 is provided in the face of the wall 10 of the freezing chamber of sufficient size to per-

mit the device to be placed into the compartment 6.

My device comprises a rack 11 having a top 12 and sidewalls 13. Formed in the top 12 is a plurality of openings 14. A plurality of ice receptacles or cups 15 are provided, each being so tapered as to permit the ice cubes to be easily removed therefrom. Each of these cups is also provided with rounded corners so that it may be kept clean without difficulty. Each of the cups is designed to fit into one of the openings 14 and each is provided with a flaring upper edge 16 which engages with the top 12 of the rack and holds the cups in position.

The chamber 6 is provided with a cover 17 for closing the opening 9 in the wall 10. This cover is preferably attached to the rack 11, so that it is removed with the rack, when the same is withdrawn from the chamber. A suitable handle 18 is provided on the cover. It is obvious that the cover may be made separate from the rack and pivotally attached to the wall 10.

From the foregoing, it will be obvious that any number of the cubes of ice may be removed from my device by taking the desired number of cups from the rack, without disturbing the other cups or the ice cubes contained therein.

Obviously some modifications of the details herein shown and described may be made without departing from the spirit of my invention or the scope of the appended claims; and I do not therefore wish to be limited to the exact embodiment herein shown and described.

Having thus described my invention what I claim is:

1. An ice form for the production of individual blocks of ice in mechanical refrigeration comprising a rack having a top formed with a plurality of individual openings and with means at the bottom thereof for slidably supporting the same, and a plurality of removable, individual cups fitting into the openings and supported by the rack.

2. An ice form for the production of individual blocks of ice in mechanical refrigeration comprising a rack having a top formed with a plurality of individual openings and with side walls for slidably supporting the same, and a plurality of removable, individual cups fitting into the open-

ings, the cups having flanged upper edges, whereby they are supported by the rack.

3. An ice form for the production of individual blocks of ice in mechanical refrigeration comprising a rack having a top formed with a plurality of individual openings and with side walls for slidably supporting the same and a plurality of removable, individual cups fitting into the openings and supported by the rack, the cups having tapered body portions and rounded corners.

4. In a mechanical refrigeration apparatus, the combination with a refrigeration

chamber, of an ice form for the production 15 of individual blocks of ice, said form comprising a rack having a top formed with a plurality of openings, side members supporting the top and so formed at their bottom portions as to enable the rack to be slidably 20 inserted in and removed from the refrigeration chamber, and a plurality of removable individual cups fitting into the openings and supported by the rack.

In testimony whereof, I have hereunto 25 signed my name.

EUGENE L. BARNES.
